UNITED STATES PATENT OFFICE.

STUART J. BEEBE, OF RICHMOND, INDIANA, ASSIGNOR TO BEEBE GLOVE COMPANY, OF RICHMOND, INDIANA, A CORPORATION OF INDIANA.

GLOVE.

Application filed November 1, 1922. Serial No. 598,394.

This invention relates to a glove, and particularly to the type of cloth working gloves having leather facings for increasing the wearing qualities thereof.

5 Gloves of this type heretofore used have been so made that many seams were exposed to wear in such a manner that the gloves were frequently ripped and made useless before the surfaces of the palm, thumb and fingers were worn through. One object of this invention is to provide a glove which is so cut and stitched that the seams thereof will not be thus exposed thereby increasing the life and wearing qualities of the glove.

10 Since working gloves of the above type must be inexpensively made, great care in the formation of the seams thereof is not possible with the result that the gloves heretofore used have had large seams between the fingers that prevented the wearer from getting his fingers close together and thus from firmly and securely grasping objects and applying the maximum strength and efficiency in any given task.

15 Accordingly, a further object of this invention is to provide an inexpensive working glove which is so constructed that all finger and thumb seams are thrown to the back of the glove and to provide a protected seam at the base of the second and third fingers that will form a natural hinge for the finger portions, thereby providing a better fitting and more flexible glove that will closely adhere to the hand and enable the wearer to obtain a firmer grasp on objects handled.

20 The invention will best be understood by reference to the accompanying drawings which illustrate one embodiment of the inventive idea. It is to be expressly understood, however, that said drawings are for the purposes of illustration only and are not to be construed as definitive of the limits of the invention, reference being had to the appended claim for that purpose.

25 Referring to the drawings, wherein similar reference numerals are employed to designate like parts in the several views,

30 Fig. 1 is a plan view of the palm side of a glove embodying the present invention;

35 Fig. 2 is a plan view of the back of the glove illustrated in Fig. 1;

Fig. 3 is a section on the line 3—3 of Fig. 1;

Fig. 4 is a plan view of the leather used in forming the palm portion of the glove;

Fig. 5 is a plan view of the piece of leather used to form the back of the thumb;

Fig. 6 is a plan view of the piece of leather used to form the inner surface of the second and third fingers;

Fig. 7 is a similar view of one of the pieces of leather employed to face the back of the tips of each of the fingers;

Fig. 8 is a similar view of the piece of leather employed to reinforce the heel of the palm; and

Fig. 9 is a like view of the strip of leather used to protect the hinge seam at the base of the second and third fingers.

In the form shown, the glove comprises a single cloth portion 10 cut in the usual manner to form a glove which covers all of the hand except the back of the thumb. Any suitable and well known method may be employed for forming the cloth portions of the glove, and for this reason the details of these portions are not illustrated. The cloth used is preferably one having a hard exterior finish and a soft inner surface. Stitched to the lower edge or wrist of portion 10 is a gauntlet 11 of the well known type comprising an outer layer of cloth, preferably similar to that used in portion 10, and an inner layer of stiff, form-retaining cloth, but said gauntlet may be formed in any other suitable and well known manner. Stitched to the outer side of portion 10 is a piece of leather 12 having palm portion 13, inner thumb portion 14, first finger 15 and fourth finger 16. Sewn to thumb portion 14 and gauntlet 11 is the upper or rear leather thumb portion 17. Leather portion 18, shown in Fig. 6, is folded along the slit 19 cut therein, and edges 20, 21 turned toward the opposite edges thereof, and this portion is stitched, along slit 19, to slit 24 formed in leather portion 12, so that the part of leather portion 18 extending from slit 19 to end 22 forms the inner surface of the second finger while the part extending from slit 19 to end 23 forms the inner surface of the third finger. Portions 14, 15, 16, 17 and 18 are of such size that the finger seams 15', 16' and 18' are thrown well to the back of the glove.

It will be apparent that a seam is formed at the base of the second and third fingers

and in order to protect this seam there is inserted therein a welt-like strip 25 (Fig. 9) in such a manner that the edge 26 thereof is stitched between the leather portions 12 and 18, adjacent slits 24 and 19. The opposite edge 27 of strip 25 extends upward along the second and third fingers and is free and unattached. It not only protects the seam at the base of the fingers from wear but acts as a natural hinge for the finger portions. When the fingers of the hand are contracted in order to grasp an object, there is a natural depression at the base of the fingers into which said seam projects, thereby filling the same and greatly aiding in the firmness with which an object may be grasped. The ends of strip 25 are secured in the crotch seams between the first and second fingers and between the third and fourth fingers. Since three sides of strip 25 are thus stitched, the upper free edge thereof is snugly held against the fingers.

The ends of the fingers of a glove are subjected to considerable wear on both sides and the back, and, in order to protect these parts, a small strip of leather 28 is stitched to the upper surface of the first joint of each of the fingers as is illustrated in Fig. 2.

To prevent ripping of the wrist seam 29, at the upper edge of gauntlet 11, due to the wear at this point, a semi-circular piece of leather 30, Fig. 8, may be stitched to gauntlet 11 and wrist seam 29, as is illustrated in Figs. 1 and 3.

It will thus be perceived that I have provided a glove that is inexpensive to manufacture and yet one which is particularly adapted to hard use. The various parts of the glove are so associated that there are only two finger crotch seams, which seams together with the seam at the base of the second and third fingers are strengthened and protected by means of the welt-like strip 25. While the embodiment shown in the ac-

companying drawings has been described with considerable particularity, it is to be expressly understood that the invention is not limited thereto, since various changes may be made in the arrangement, seams, and proportioning of the various parts without departing from the scope of the invention. Reference is therefore to be had to the appended claim for a definition of the limits of the invention.

What is claimed is:—

A cloth glove having leather reinforcing facings secured thereto, said facings comprising a limited number of blanks, including a major blank having its sides straight and parallel, and one end straight for the greater portion of its length and at right angles to the said parallel sides, a rounded projecting portion formed on said straight end, the continuing curve of which is defined in the body portion of the blank by a pair of inwardly extending slits whereby a tab is provided adapted to form a reinforcement for the inner surface of the thumb, the other end of the said blank being cut to form coverings for the inner surfaces of the first and fourth fingers with the central portion of the blank forming a covering for the palm, a substantially oval shaped blank having a slit therein constituting a reinforcement for the inner surfaces of the second and third fingers, an irregularly shaped blank forming a reinforcement for the back of the thumb, a semi-circular shaped blank forming a reinforcement for the heel of the palm, a welt-like strip forming a reinforcement for the base of the second and third fingers, and a plurality of substantially rectangular blanks forming reinforcements for the backs of the first joint of each finger.

In testimony whereof I have signed this specification.

STUART J. BEEBE.
